COMBINED CASKET AND GRAVE VAULT

William S. Stone, Green Township, Hocking
County, Ohio

Application August 27, 1937, Serial No. 161,304

2 Claims. (Cl. 27—6)

This invention relates to caskets and vaults therefor and has for its object to provide an improved construction whereby the life of the casket is prolonged and the vault adapted to deter, if not thwart attempts to steal the corpse or valuable contents in the casket. Another object of the invention is to provide means whereby the casket is protected from puncturing in the handling and transporting of it. Other objects will 10 be apparent from the disclosure herein.

The invention is embodied in the construction and combination of parts herein shown and described, the features of novelty being finally claimed.

15 In the accompanying drawing—

Figure 1 is a view partially in longitudinal section on line I—I, Fig. 2 and partly in elevation looking at the side of the structure.

20 Fig. 2 is a transverse section on the line II—II, Fig. 1, looking to the left.

In the views the character 5 designates the body of the casket, the same being of the usual form and dimensions for the reception of the body of the deceased. The structure 5 will be 25 made of a single sheet of soft metal, as for example copper, or of a metal or alloy having attributes of copper, the said structure including an outwardly extending flange 5^a all around its rim to receive a gasket 5^b. Internally the body 5 of the casket has soldered or otherwise secured to it near its upper edge one leg of an angular piece of suitable metal, the projecting leg 6 of which 30 constitutes a seat for a wooden frame 7. Hinged to said wooden frame 7 is the casket lid or cover 8, the latter being made of wood or metal or a combination of wood or metal, the object being to avoid embarrassing metallic sounds when the casket is closed with the lid upon the conclusion 35 of the funeral services.

40 The vault structure includes a hood 10 also made of sheet copper or metal similar to that of the body, said hood having its top provided with parallel grooves 10^a and a shoulder 10^b around its margin to fit and rest on the gasket 5^b so that 45 when the vault structure is in place air cannot pass into the casket.

11 designates a protective member for the top of the vault, said protective member being made of sheet steel and is arched or rounded in form 50 at the top. The margins of this protective member 11 are bent inward and formed with a flange 11^a and connected with the grooves of the top of the copper hood 10 by solder. The connection just described by reason of its form and the position shown, that is near the lateral walls of the

casket body, tends to prevent the collapse of the sides of the casket. The arched protective member 11 can be provided with one or more internal zig-zagged bracing plates of steel 13, the sections of which can be soldered or welded to the steel member 11 before it is connected with the copper hood. The end legs of said bracing plate 13 are secured by soldering or welding between top and bottom portions of said protecting member 11. Such a bracing device tends effectively to sustain 10 the load of the soil that is thrown into the grave on top of the vault. The hood can, if desired, be copperized or made rust proof, so called, inside and out.

If the bottom of a casket be made of copper 15 alone, it is likely to be punctured by the spurs employed on trucks for transportation hence I provide a bottom plate of steel 12 having an upwardly extended flange all around that can be secured by soldering to the side of the casket or to an ornamental trim 15 of wood around the bottom portion of the casket. To avoid the danger of slipping when carried on a truck either with or without spurs the bottom of the steel 20 armor 12 is covered with suitable paper board or other soft material that can be slightly penetrated 25 by spurs on the truck.

The flange of the steel bottom can have integral therewith or welded thereto upwardly extending therefrom suitable arms 12^a provided with lugs 30 12^b adapted to be engaged by spring steel catches 10^c soldered on the lower margins of the skirt of the vault. In lieu of or in addition to the locking means just described other catches can be soldered to the inner side of the skirt of the vault 35 to engage the lower side of the flange when the vault has been lowered on the casket to its home position.

Handles 14 of the ordinary form for pall bearers and other attendants are provided. These 40 handles can be riveted to upward extensions or arms 12^a of the bottom protecting plate 12. These handles have a firm connection with the bottom plate 12 which in effect forms a sort of shallow box in which the copper body of the 45 casket is supported and contained.

For ornamentation both the interior and exterior of the casket can be covered with paper board lined with fabric of pleasing designs.

If, after the casket and vault are lowered into 50 the grave, water should accumulate in the space between the casket and vault it cannot rise to flow into the casket because of the resisting confined air in the said space. By reason of this construction the body of the deceased may be 55

preserved for a long period of time especially if it has been embalmed.

While it is true, that given time and tools, theft of the contents of the grave cannot be prevented, yet with the construction herein shown the hard steel rounded and arched cover unlawful attempts to penetrate the vault or raise the same will be greatly discouraged.

From the construction shown and described it is obvious that in course of time the steel portions can rust and break down yet the copper portions will remain intact for some centuries of time in ordinary circumstances. That this is true is evidenced by the fact that objects or artifacts of copper made in prehistoric times have been disinterred in nearly their pristine form and condition.

The forms of the parts can be changed without departing from the gist of the invention as claimed. Where I speak of copper in the claims I intend to include metal having a durable quality like that of copper.

What I claim is:

1. A combined casket and grave vault including a casket constructed of leak proof sheet copper having its bottom and adjacent side portions lined with sheet steel, a vault portion to inclose the casket consisting of an external arched pro-

tective cover of sheet steel having inwardly turned tongue and groove margins, and a zig-zag interior bracing member for said arched cover of sheet steel footed on said inwardly turned margins, a hood of sheet copper for the casket having its upper portion bent into permanent engagement with said inwardly turned margins of the arched cover, the skirt of said hood being of ample depth and spaced from the exterior of the casket to provide a confined water excluding air body between the casket and vault hood. 10

2. A combined casket and grave vault including a casket constructed of leak proof sheet copper, a vault portion to inclose the casket consisting of an external arched protective cover of sheet steel 15 having inwardly turned tongue and groove margins, and a zig-zag interior bracing member for said arched cover of sheet steel footed on said inwardly turned margins, a hood of sheet copper for the casket having its upper portion bent into 20 permanent engagement with said inwardly turned margins of the arched cover, the skirt of said hood being of ample depth and spaced from the exterior of the casket to provide a confined water excluding air body between the casket and 25 vault hood.
